THOMAS DANQUARD, OF NEW YORK, N. Y., ASSIGNOR TO KOHLER & CAMPBELL, OF NEW YORK, N. Y., A FIRM.

PNEUMATIC-MOTOR VALVE MECHANISM FOR AUTOMATIC PIANO-PLAYERS.

SPECIFICATION forming part of Letters Patent No. 737,363, dated August 25, 1903.

Application filed April 26, 1902. Serial No. 104,739. (No model.)

To all whom it may concern:

Be it known that I, THOMAS DANQUARD, a citizen of the United States of America, residing at the borough of Manhattan, city of New York, State of New York, have invented certain new and useful Improvements in Pneumatic-Motor Valve Mechanism for Automatic Piano-Players, of which the following is a specification.

10 My invention has for its object to provide simple and efficient valve mechanism controlling the operation of a pneumatic-motor which actuates the traveling music-sheet of an automatic piano-player.

15 The invention includes a novel arrangement of pairs of valves operating at the air-passages of the individual motor-pneumatics which open and close to rotate the driving-shaft from which the music-sheet is actuated

20 and also includes a novel relative arrangement of valves and an auxiliary pneumatic for variably controlling the "tempo" of the music and also at times causing high speed of the motor for assuring quick rewinding of 25 the music-sheet, all as hereinafter described and claimed.

Reference is made to the accompanying drawings, forming part of this specification, and in which—

30 Figure 1 is a plan view of the pneumatic-motor and its valve mechanism and a portion of the main wind-chest with parts broken away and removed. Fig. 2 is a vertical longitudinal sectional elevation thereof, and Fig.

35 3 is a detail vertical cross-sectional view more especially illustrating the pair of valves and the air-passages of one of the motor-pneumatics.

In the drawings the numeral 5 indicates the

40 wind-chest of the pneumatic-motor which is exhausted by a main bellows, (not shown), which draws air from the main wind-chest 6, with which communicate by suitably-valved ports the small pneumatics to whose movable

45 walls are coupled the hammers which act on the keys of a piano to automatically play it in well-known manner. These hammer-operating valved pneumatics also are not shown, as they form no part of this invention. The wind-

50 chest 6 communicates directly with the motor wind-chest 5 through a passage 7 and also

communicates indirectly with it through another passage 8 9, in which is interposed an air-tension-controlling pneumatic 10, the part 8 of said passage leading from chest 6 into 55 the pneumatic 10 and the part 9 of it leading from said pneumatic into the motor wind-chest 5, preferably at a point near the place of opening into said chest of the direct air-passage 7 above mentioned. 60

The auxiliary pneumatic 10 preferably has the usual internal flap-valve 11, which automatically cuts off air-exhaust through the passage 8 9, more or less, as determined by movement of the outer flexible wall of this pneumatic, which carries a lip 12, engaging the valve. This flexible pneumatic wall is moved by the air exhaust of suction and against the force of an expanding-spring 13, which normally tends to fully open the pneumatic 10 and 65 its valve 11. The operation of this auxiliary valved pneumatic 10 11 relatively to the air-tension in or of the main bellows to control any desired speed of the motor and of the music-sheet is well known in this art. It 70 will, however, be noticed that I have specially arranged the auxiliary valved pneumatic 10 11 in such relation to the air-passages 7 8 9 and the motor wind-chest 5 as to permit location of both motor-controlling valves 14 15 75 80 directly at or within the motor wind-chest 5, to which are fastened the series of pneumatics 16, by or from which the motor driving-shaft 17 is rotated, as presently explained.

The reciprocating slide-valve 14 preferably 85 has a slot which cooperates with the reduced or narrow throat of the passage 9 to permit variable volume of air to pass through the wind-chest 5 as may be necessary to cause rotation of the motor driving-shaft 17 at any 90 speed required by the desired tempo of the music which is controlled by the speed of travel of the music-sheet, whose take-up and delivery rolls are actuated by a belt 18, running from a pulley 19 on the motor driving-shaft 17 and in well-known manner not necessary to show or further describe. The stem 20 of valve 14 is shown coupled by a link 21 to a lever 22 in easy reach of the performer, who by adjusting it may open the passage 9 95 100 more or less to assure faster or slower speed of rotation of the driving-shaft 17, and thus

control the tempo of the music. The reciprocating slide-valve 15 has a stem 23, here shown coupled by a link 24, a rocking lever 25, and a rod 26, with another lever 27 in reach 5 of the performer. This lever 27 preferably has other connections (not herein shown) for automatically uncoupling the take-up roll of the music-sheet from the motor-shaft and coupling thereto the delivery-roll, so that one 10 motion of said lever 27 will fully open the large direct air-passage 7 and cause high speed of the motor to assure quick rewinding of the music-sheet on the delivery-roll at the finish of a piece of music or when repeating parts 15 thereof. Each reciprocating valve 14 15 is preferably held to its seat by a spring 28. (Best shown in Fig. 1 of the drawings.) No matter at what speed the motor driving-shaft 17 may be rotated by variable air-supply through the 20 passage 8 9 past the valves 11 14 or through the passage 7 past the valve 15 the operation of the motor is directly controlled by pairs of valves, one pair for each motor-pneumatic 16, and which constitute an important feature 25 of my invention, to be presently described.

The motor-shaft 17 is journaled in bearings 29, fixed to the wind-chest 5, and has a series 30 of cranks 30, which when three motor-pneumatics 16 are used are set one hundred and twenty degrees in advance of each other. These cranks are coupled by rods 31 to the movable walls of the pneumatics 16, which when vibrated impart rotation to the driving-shaft as the pneumatics open and close. These 35 rods 31 are each coupled preferably by an extensible or telescoping link 32 33 with an up-bent arm 36 of a duplex tappet device 37 38, adapted to operate the pair of valves 39 40 of each pneumatic 16. I prefer to make the link 40 part 32 with one right-angularly bent end which has a bearing in the corresponding pneumatic-connecting rod 31 and receives a nut 34, which detachably couples the parts 31 32 together. At its other end the link part 32 45 has a screw-thread 35, fitting a female thread in the other link part, 33, in which the bent end of the tappet-arm 36 has a bearing. When the nut 34 is removed, the part 32 can be slipped from the rod 31 to permit said part 32 50 to be turned by its thread 35 in the part 33 for lengthening or shortening the link 32 33 as may be necessary to cause accurate throw of the tappets 37 38, and thereby actuate the two valves 39 40 of each pneumatic at proper 55 times to assure easy and uniform rotation of the driving-shaft from the pneumatics 16 at any desired speed.

The valve 39 is arranged at an opening between the exhaust - air chamber 41 of the 60 motor wind-chest 5 and a passage 42, leading to the pneumatic 16, and the valve 40 controls an air-opening 43 from said passage 42 to the atmosphere. The stem of the inner valve 39 is linked to a lever 44, which is fulcrumed at 45 to the chest 5, and the outer valve 40 is held to another lever, 46, fulcrumed at 47 to said chest. The tappets 37

38 underlie the free ends of the respective levers 44 46, so that when the tappet devices are rocked by the links 32 33 from the oscillatory rods 31, coupling the pneumatics 16 to the cranked driving-shaft 17, the valves 39 40 will be alternately opened and closed to successively connect the pneumatics 16 with the exhaust-chamber 41 and with the atmosphere to cause opening and closing of the pneumatics for rotating the driving-shaft 17. Suitable light springs 48 act on the valve-levers 44 46 to promote prompt closure of the valves 39 40, as permitted by the rocking of 80 the tappet devices.

I specially mention making the valve-operating tappet device 37 38 of or from one piece of wire or material adapted for rocking in suitable bearings on the motor wind-chest 85 5. As a further improvement I make the arm 36, by which the tappets 37 38 are rocked, as an integral extension of the same wire. I further specially mention that the valve-operating tappets 37 38 are so proportioned relatively to the arm 36 and to the parts 30 31 32 33 that the valves 40 always close just before the valves 39 open, thereby avoiding power-wasting leakage of air during operation of the motor-pneumatics 16 by exhaust 95 of air through the wind-chest 5 by the main pedal - operated bellows of the instrument, thus assuring proper starting of the motor and also maintaining most regular rotation of the music-sheet-driving shaft 17 at any 100 desired speed to accommodate the tempo of the music.

By my special arrangement of levers 44 46, connected to each pair of pneumatic-controlling valves 39 40 and the tappet device 37 105 38, actuating each pair of valve-levers from a link coupling the tappet device to the pitman 31 of a pneumatic, the valves are directly lifted to open them without the aid of springs, which are liable to derangement, and there is no appreciable loss of power or excessive disarranging wear of parts by friction which occurs when pneumatic - valves are opened by cams on the main driving-shaft of the motor acting on levers connected to the 115 valves, nor is there any such loss of power by friction as occurs when sliding pneumatic-valves are used and are actuated by pitmen connecting the pneumatics with the main driving-shaft. Furthermore, all parts of my 120 pneumatic duplex - valve mechanism are at all times accessible for adjustment or repair and said valve mechanism is not only certain and positive in its action, but its construction and mode of operation combine to make 125 it very efficient and durable in use and very well adapt it for hard service without requiring frequent attention for readjustments or repairs.

The novel arrangement of the main motor-controlling valves 14 15 in the wind-chest of the motor-pneumatics relatively to the auxiliary pneumatic 10, its valve 11, and the air-passages 7 8 9, and also relatively to the pneu-

matic-valves, makes a very simple, efficient, compact, and comparatively inexpensive construction.

I am aware of a prior automatic piano in which a single perforated slide-valve is used at a music-sheet-motor wind-chest to control flow of air through the motor-pneumatics and wind-chest to two separate chambers of a main wind-chest, from which air is exhausted by a main bellows. One of these chambers communicates with a pneumatic valved air-current regulator interposed in an indirect air-passage between said chamber and the bellows for automatically regulating the desired tempo of the music, and the other of said wind-chest chambers may by adjustment of the same valve put the motor wind-chest directly in communication with the main bellows for inducing unobstructed air-current through the motor to assure its high speed and consequent rapid rewinding of the music-sheet. Such subdivision of the prior main wind-chest into two independent chambers not only increases the cost of construction, but promotes liability to air leakage at interior joints which are not readily accessible for inspection and repairs and are injuriously affected by changes of weather and of temperature, to which instruments of this class are peculiarly sensitive. With my motor wind-chest 5, having but one chamber common to the motor-pneumatic valves and to the two independent valves 14 15, which control the direct and indirect passages 7 and 8 9, respectively, to the single-chambered main wind-chest 6, and with the pneumatic valved air-current regulator 10 11, interposed in said passage 8 9, I wholly avoid inaccessible interior joints at the main wind-chest and assure effective operation and great durability of all the working parts, which may be reached easily and quickly for examination and repair without dismembering any vital part of the instrument.

45 I claim as my invention—

1. The combination, with the motor wind-chest having air-exhaust chamber and air-passages, the motor-pneumatics, the motor driving-shaft, oscillatory rods connecting the movable walls of said pneumatics with the driving-shaft, and pairs of valves acting at openings of the motor wind-chest leading to the pneumatics and to the atmosphere, of levers coupled to the valves, tappets acting on said levers for opening the valves, and links coupling the tappets with the oscillatory rods connecting the motor-pneumatics and driving-shaft.

2. The combination, with the motor wind-chest having air-exhaust chamber and air-passages, the motor-pneumatics, the motor driving-shaft, oscillatory rods connecting the movable walls of said pneumatics with the driving-shaft, and pairs of valves acting at openings of the motor wind-chest leading to the pneumatics and to the atmosphere, of levers coupled to the valves, tappets acting on

said levers for opening the valves, and links coupling the tappets with the oscillatory rods connecting the motor-pneumatics and driving-shaft, said valves and their operating devices being relatively adjusted to allow the valves at the atmosphere-openings of the motor wind-chest to close before the valves open at the air-exhaust chamber of said wind-chest. 75

3. The combination, with the motor wind-chest having an air-exhaust chamber and air-passages, the motor-pneumatics, the motor driving-shaft, oscillatory rods connecting the movable walls of said pneumatics with the driving-shaft, and pairs of valves acting at openings of the motor wind-chest leading to the pneumatics and to the atmosphere, of levers coupled to the valves, tappets acting on said levers for opening the valves, and lengthwise-adjustable links coupling the tappets with the oscillatory rods connecting the motor-pneumatics and driving-shaft and permitting regulation of the valve action. 85

4. The combination, with the motor wind-chest having air-exhaust chamber and air-passages, the motor-pneumatics, the motor driving-shaft, oscillatory rods connecting the movable walls of said pneumatics with the driving-shaft, and pairs of valves acting at openings of the motor wind-chest leading to the pneumatics and to the atmosphere, of levers coupled to the valves, tappets actuating said valve-levers and comprising bent portions of an integral oscillatory wire or rod, 95 and links coupling said integral tappet devices with the oscillatory rods connecting the motor-pneumatics and driving-shaft. 100

5. The combination, with the motor wind-chest having air-exhaust chamber 41 and air-passages 42, 43; the pneumatics 16, driving-shaft 17, and rods 31 connecting parts 16, 17, of a pair of valves 39, 40 for each pneumatic 16, an integral tappet device actuating the valves of each pneumatic and comprising oppositely-arranged cranked portions 37, 38, and an arm 36; pairs of levers 44, 46, actuated by the tappets 37, 38, and carrying the respective valves 39, 40 of each pneumatic, and links coupling the connecting-rods 31 110 with the tappet-device arms 36 of the respective pneumatics 16, substantially as described. 115

6. In valve mechanism of the character described, the combination of a main wind-chest, a music-sheet-motor wind-chest, valves at said motor wind-chest controlling the motor-pneumatics for operating the motor and music-sheet, an auxiliary pneumatic communicating with both the main and motor wind-chests and having a valve actuated 120 automatically by the air-exhaust, and two independently-operative valves at the motor wind-chest one of said valves being adjustable for governing the "tempo" of the music and controlling the indirect passage between 125 the main and motor wind-chests in which the pneumatic air-current regulator is interposed, and the other of said valves controlling the direct passage between the main and

the motor wind-chests and being adjustable to permit unobstructed air-current through the motor-pneumatics and assure high speed of the motor while rewinding the music-sheet.

5 7. In valve mechanism of the character described, the combination of a main single-chambered wind-chest 6, a music-sheet-motor wind-chest 5 and valves at the latter inducing operation of the motor-pneumatics and 10 rotation of the coupled music-sheet-driving shaft, an automatic regulator comprising a pneumatic 10 having valve 11 and held to the main wind-chest, said main and motor wind-chests being connected by a direct passage 7, and also by an indirect passage 8 9

controllable by the interposed automatic regulator 10 11, a valve 14 in the motor wind-chest 5 controlling air-current through the motor-pneumatics and said chest and the regulator 10 11 for governing the "tempo" of the music, a valve 15 in the motor wind-chest 5 adjustable to permit unobstructed air-current through the motor-pneumatics for quickly rewinding the music-sheet, and means for independently operating the valves 14, 15, substantially as herein set forth. 20 25

THOMAS DANQUARD.
